UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY, A CORPORATION OF NEW JERSEY.

DESIGN FOR A RADIATOR CAP.

Application filed February 11, 1926. Serial No. 16,484. Term of patent 7 years.

To all whom it may concern:

Be it known that I, EDWARD B. NOWOSIELSKI, a citizen of the United States, residing at Bloomfield, in the county of Essex, State of New Jersey, have invented certain new and useful Improvements in a Design for a Radiator Cap, of which the following is a description, reference being had to the accompanying drawing, and to the figures of reference marked thereon.

Figure 1, is a front elevation of my ornamental design for a radiator cap.

Figure 2, is a side view of Figure 1.

I claim—

The ornamental design for a radiator cap, substantially as shown.

In testimony whereof, I affix my signature.

EDWARD B. NOWOSIELSKI.
